UNITED STATES PATENT OFFICE.

THOMAS J. STURTEVANT, OF WELLESLEY, MASSACHUSETTS, ASSIGNOR, BY MESNE ASSIGNMENTS, TO STURTEVANT MILL COMPANY, OF BOSTON, MASSACHUSETTS, A CORPORATION OF MASSACHUSETTS.

SEPARATOR.

1,353,547.

Specification of Letters Patent. Patented Sept. 21, 1920.

Application filed October 18, 1917. Serial No. 197,330.

To all whom it may concern:

Be it known that I, THOMAS J. STURTEVANT, a citizen of the United States, residing at Wellesley, county of Norfolk, and State of Massachusetts, have invented an Improvement in Separators, of which the following description, in connection with the accompanying drawings, is a specification, like characters on the drawings representing like parts.

The invention hereinafter described relates to separators for grading materials, and more particularly to an improved screen therefor.

These separators usually comprise a casing having a feed box at the top thereof which delivers the material to be graded to the upper surface of an inclined, vibrated screen in the casing. The finer material passes through the screen, and the coarser material flows along the screen, the former being delivered through one outlet and the latter being delivered through another outlet in the casing.

In order to produce efficient grading of the material, it is essential that the screen clothing should be stretched tightly on its support. Sometimes the screen clothing is adjustably connected by bolts directly to the casing of the separator, and sometimes the clothing is stretched on a frame mounted within the separator. Heretofore, the devices employed to stretch the clothing have been applied to the margin of the clothing in such a manner that the stretching thereof increased the perimeter of the clothing or frame, and thus only a limited stretching of the clothing could be obtained. One of the objects of the present invention is to provide simple and effective means whereby the screen can be stretched as required without increasing the perimeter thereof.

The vibration of the clothing and the weight of the material thereon tends to stretch certain portions thereof more than others. Another object of the invention is to provide means whereby the clothing may be readily stretched to eliminate any local bagging thereof.

A frame has been used to support the clothing having cross bars tending to spread the side bars of the frame to stretch the clothing, as shown in Letters Patent of T.

L. Sturtevant, No. 1,125,762, dated January 19, 1915, but the construction is such that there is no provision for the desirable application of the vibrating means to the screen within the boundaries of the frame. Another object of the invention is to provide a frame having resilient bars and one or more resilient cross bars or members which will tend to stretch the clothing, but will permit the desirable application of the vibrating means to the screen within the boundaries thereof, and without interfering with the stretching of the clothing or obstructing the free flow of the material to be graded along the screen.

Where pins have been used to transmit blows from hammer devices to the screen clothing, they have been applied directly to the clothing at distributed points thereon, so that the areas of the clothing adjacent said pins have experienced greater stretching and bagging than portions more remote from said pins. The cross bar or bars may desirably serve to distribute the blows from the pins to the clothing and eliminate local distortion of the clothing therefrom.

The character of the invention may be best understood by reference to the following description of one good form thereof shown in the accompanying drawings, wherein:

Figure 1 is a vertical section through a separator illustrating the invention;

Fig. 2 is a transverse section taken on line 2-2 of Fig. 1;

Fig. 3 on an enlarged scale is a plan of the screen;

Fig. 4 is a plan of a portion of a bridge bar and a side bar of the screen showing the means connecting them;

Fig. 5 is an end view of the construction shown in Fig. 4;

Fig. 6 is a vertical section taken on line 6-6 of Fig. 4;

Fig. 7 on an enlarged scale is a sectional detail showing the relation of one of the cross bars with the stretching bar;

Fig. 8 is a vertical section taken on line 8-8 of Fig. 7;

Fig. 9 is a detail to be referred to;

Fig. 10 is a plan detail showing one of the screen positioning plates above the screen supporting springs; and

Fig. 11 is a section taken on line 11—11 of Fig. 10.

Referring to the drawings, the separator shown therein as an exemplification of the invention, comprises a frame 1 (Fig. 1) having a main frame, in the present instance, in the form of an inclined casing mounted thereon provided with a bottom 3, side walls 5, and a cover 7 with its upper end connected by a hinge 9 with the casing, and its lower end adapted to rest upon a transverse member 11 adjacent the lower end of the casing.

A trough 13 at the top of the casing contains a screw conveyer 15 adapted to feed the material to be graded along the trough over a feed board 17, and deliver the same to a screen mounted within the casing.

This screen, in the present instance, of the invention, comprises a frame having longitudinal side members conveniently in the form of angle bars 19 (Fig. 3), and end members conveniently in the form of flat bars 21 having upturned ends 22 riveted or otherwise secured to the inner faces of the upper flanges of the side bars. Screen clothing 23 or other suitable screening material may be stretched on and riveted or otherwise secured to said frame.

The side bars of the frame may be sufficiently light and of a resilience such that they may be flexed inward between their points of connection with the end bars when the screen clothing is secured thereto. These bars will then tend to straighten and automatically stretch and maintain the clothing properly tensioned. One or more transverse members may be provided, in the present instance, in the form of channel bridge bars 25 connected to the side bars by plates 27 (Figs. 4, 5 and 6), conveniently triangular in shape, having ends 29 bent inward and riveted or otherwise secured to the under faces of the channel bars. The ends 31 of the depending flanges of the channel bars may engage the inner faces of said plates and contribute to the strength of the construction.

The bars and the plates have an inherent resiliency such that they tend to thrust outward or straighten the side bars, and thus do not detract from the tensioning effect of the side bars, but on the contrary, contribute to this effect. The bridge bars are spaced above the screen clothing a sufficient distance to allow flow of the material to be graded beneath them without obstruction thereto. Said bars may not only serve to tend to straighten the side bars of the frame and stretch the screen clothing, but may also serve to transmit and distribute the blows of the hammer vibrating means thereto as hereinafter described.

Next will be described the means for stretching the screen clothing to eliminate

local bagging or distortion thereof, and for stretching the clothing without increasing the perimeter thereof. This means, in the present instance of the invention, comprises a stretching member in the form of a U-shaped bar 33, preferably extending the length of the screen, and having its ends superposed on and riveted to the end members 21 of the frame. The legs 35 (Fig. 7) of said member may be bent to present feet 75 which may be riveted or otherwise secured to portions of the screen clothing. In the form of the invention shown, these feet are secured to the screen clothing adjacent the longitudinal center thereof. The inherent 80 resilience of the stretching member preferably tends to draw the feet thereof toward one another, and thereby continuously tends to stretch the screen clothing. Said member may be provided with adjustable means 85 for controlling the stretching of the screen clothing, and for limiting the outward movement of the feet thereof. In the present instance of the invention, this means comprises a series of bolts 39 (Figs. 1 and 7) 90 entered through registering holes in the legs of said member. The nuts 41 of the bolts may have flat faces thereof engaging one of the feet of the member to prevent rotation thereof, and the heads of the bolts may be 95 formed to receive a screw driver for adjusting the same. Split spring washers 43 of usual construction may be confined between the heads of the bolts and the outer face of one of the legs of said member, and 100 serve to permit turning of the screws in one direction and lock the same against turning in the opposite direction.

The stretching device for the screen may be located within the boundaries of the frame, and stretch the screen clothing without increasing the perimeter of the frame. As a result, the original shape and size of the frame are maintained.

If fine mesh, light screen clothing is used, 110 it will readily flex and pucker as at 45 (Fig. 7) between the feet of the stretching bar, where they are drawn toward one another, but if coarse, heavy screen clothing is used, it would be divided into separate sections 115 having their inner margins secured to the feet of the stretching member.

The stretching bar may be laterally flexible, so that portions of the legs thereof may be drawn together to eliminate local bagging 120 of the screen clothing. To accomplish this, the bolt or bolts connecting said legs adjacent the distorted portion of the clothing may be tightened, thereby locally flexing the legs of the bar to increase the tension on the 125 distorted portion. The bolts are readily accessible and easily adjusted, so that all local bagging can be prevented. This means for local adjustment desirably co-operates with the tensioning side bars and bridge bars 130

to maintain the clothing always properly stretched and in condition to produce most efficient screening effect.

Next will be described the means for imparting blows to the bridge bars to vibrate the screen. In the present instance of the invention, this means comprises pins 47 (Fig. 1) having lower ends adapted to rest upon bearing plates 49 secured to the tops of 10 the channel bars. The upper ends of said pins project through holes in the casing cover, and receive blows from hammer devices comprising strikers 51 having ends pivotally connected to rotors conveniently in 15 the form of hubs 53 fast on a shaft 55 journaled in bearings in brackets 57 mounted on the cover. Spring members or strips 59 may have ends mounted on and secured to brackets 61 on the cover, and have free ends 20 projecting over the upper ends of said pins to receive the blows of the strikers, protecting the ends of said pins from wear, and relieving said pins from the weight of the 25 strikers after imparting their blows thereto substantially as described in my copending application, Serial No. 192,478, filed September 21, 1917.

The flanges of the channel bars preferably engage the upper edge of the stretching 30 bar, referred to, and the blows imparted to the pins are transmitted to the screen clothing by the channel bars directly to the side bars of the frame and through said stretching member to the end bars of said frame, 35 thereby desirably distributing the vibratory effect of said blows to the screen clothing through said frame and stretching member. The construction is such that the pins are not applied directly to the screen clothing, 40 and as a result, local stretching and bagging of the screen clothing by the pins is prevented.

The channel bars serve not only to desirably distribute the vibration to the screen, 45 but also prevent the pins from projecting to the screen in the path of the material flowing down along the upper surface of the screen. As a consequence, the available screening area is increased. The bridge bars 50 may also serve as handles whereby the screen may be conveniently grasped for the purpose of insertion of the same into the casing, and removal of the same therefrom.

The screen may be supported in the casing on the upper portions of curved leaf 55 springs 63 (Figs. 1 and 2) secured on Z-bars 65 mounted on the bottom of the casing adjacent the side walls thereof. To guide the screen into position on said leaf 60 springs, prevent injury to the screen clothing from said springs, and limit downward and lateral movement of the screen on said springs, stop plates 67 (Figs. 10 and 11) may be riveted or otherwise secured to the side 65 bars of the frame and have portions pro-

jecting inward beneath the screen clothing. Rims depend from said plates and have inclined portions 69 which may engage the inner edges of the springs and guide the screen into position with its side bars above the 70 springs. End portions 71 of said rims then engage the free ends of the springs and limit the downward movement of the screen.

To prevent the material to be graded from escaping over the sides of the screen, shield 75 plates 73 (Figs. 1 and 2) may be secured to the outer faces of the upstanding flanges of the side bars of the screen frame, and said plates may overlap similar plates 77 secured to and depending from the under face of the 80 cover.

By my invention, a screen is provided which is simple and strong in construction. The screen clothing thereof is readily maintained in efficient tension, and the blows of 85 the vibrating devices are so distributed to the screen that distortion and wear of the screen clothing are reduced to a minimum.

It will be understood that the invention is not limited to the specific embodiment 90 shown, but that various deviations may be made therefrom without departing from the spirit and scope of the appended claims.

What is claimed is:

1. A screen for separators, comprising a 95 frame having side and end members, screen clothing secured to said side members, a member extending along said clothing intermediate and substantially parallel to the side members of said frame and secured to the 100 end members of said frame, and means co-operating with said intermediate member to stretch the clothing, said intermediate member and stretching means co-operating therewith located in their entirety above said 105 clothing.

2. A screen for separators, comprising a 110 frame, screen clothing secured to said frame, a channel above said clothing having flanges projecting downward toward said clothing to prevent the material to be graded from entering and choking said channel, and means co-operating with said channel for stretching said clothing with a pull thereon 115 away from opposed sides of said frame.

3. A screen for separators, comprising a 120 frame having side and end members and a channel intermediate said side members and secured to said end members; screen clothing secured to said side and end members and to the flanges of said channel, and means relatively to adjust said flanges to tension the clothing.

4. A screen for separators, comprising a 125 frame, screen clothing secured thereto, a device extending along said clothing intermediate opposed sides of said frame for stretching the clothing, said device having relatively adjustable members, and means co-operating with said members relatively to 130

flex said members to take up and eliminate any local sagging of the clothing.

5. In a separator for grading materials, the combination of an inclined screen comprising a frame, screen clothing secured thereto, a device extending along said clothing intermediate and substantially parallel to opposed sides of said frame for stretching said clothing with a pull in a direction 10 inward from said sides, and means operating through said stretching device for vibrating the clothing and promoting the passage of materials to be graded therethrough.
- 15 6. A separator for grading materials having, in combination, an inclined screen comprising a frame, screen clothing secured thereto, a channel above said clothing and secured to said frame, means co-operating 20 with said channel to stretch the clothing; and means to vibrate said channel and clothing.

7. A separator for grading materials having, in combination, a screen comprising a frame, screen clothing secured thereto, a channel above said clothing, means co-operating with said channel to stretch the clothing; and means including hammers and pins receiving blows from said hammers and 30 operating through said channel to vibrate said clothing.

8. In a separator, the combination of a main frame or casing; a screen frame therein comprising opposed side members, transverse members to hold said side members in spaced relation, and a stiffly resilient bridge bar provided with downwardly extending ends rigidly secured to said side members; screen clothing stretched on said screen 35 frame and spaced a substantial distance beneath said bridge bar, hammer means mounted on the main frame or casing; a cover positioned between said screen frame and said hammer means, and a pin having an end projecting through said cover to receive blows from said hammer means and an end resting on said bridge bar to vibrate said bar, frame and clothing.

9. In a separator, the combination of a main frame or casing, spring supporting

means therein, a screen frame mounted on said spring supporting means and comprising opposed side members, and a stiffly resilient bridge bar having ends secured to said side members, screen clothing stretched on said screen frame and spaced a substantial distance beneath said bridge bar, a pin resting on said bridge bar above the clothing, and hammer means mounted on said main frame or casing to strike blows on 60 said pin to vibrate said clothing.

10. In a separator, the combination of a main frame or casing; an inclined frame mounted therein comprising opposed side members and a vibratory bridge bar secured to said side members, screen clothing for grading materials stretched on said inclined frame a substantial distance beneath said bridge bar, that the latter may vibrate without interference with materials flowing 70 along said clothing, and hammer means mounted on said main frame or casing for imparting blows to said bridge bar at a point a substantial distance in from the ends thereof to vibrate said clothing through the frame 75 therefor.

11. A screen for separators, comprising a frame, screen clothing secured thereto, a bridge member extending above and transversely of the screen clothing and including 80 a channel bar having flanges projecting therefrom, and plates or equivalent elements connecting said bar with opposed sides of said frame and adapted to engage the ends of said flanges to limit flexion of said plates 85 or elements relatively to said channel.

12. A separator for grading materials having, in combination, a screen comprising a frame, screen clothing secured thereto, a stretching bar having means for stretching 90 the clothing with a pull away from opposed sides of said frame, a bridge bar extending transversely of said frame and stretching bar and secured to said opposed sides of said frame; and means to impart vibrations to 95 said bridge bar and stretching bar to vibrate said clothing.

In testimony whereof, I have signed my name to this specification.

THOMAS J. STURTEVANT.
